STOPPING MECHANISM FOR WEFT REPLENISHING LOOMS

Clifford Darwin, Worcester, Mass., assignor to
 Crompton & Knowles Loom Works, Worcester,
 Mass., a corporation of Massachusetts

Application October 3, 1940, Serial No. 359,568

14 Claims. (Cl. 139—290)

This invention relates to weft replenishing looms and it is the general object of the invention to provide means for stopping the loom if the shuttle is not properly placed to receive the incoming bobbin on a transferring beat of the loom.

Weft replenishing looms ordinarily employ a magazine to provide a supply of reserve bobbins which are moved one by one under a transerrer arm to be inserted into the depleted shuttle. The shuttle is provided with spring jaws or holding clips which retain the rings on the bobbin butts. If for any reason the shuttle is not properly placed under the magazine the reserve bobbin will be moved downwardly by the transerrer arm along a path at one side of the jaws and will not be held properly in the shuttle. Under these conditions the depleted bobbin may be incompletely discharged from the shuttle or the reserve bobbin may assume a diagonal position with one end high enough to damage the magazine or the shuttle when it is picked.

So-called shuttle feelers have heretofore been used to prevent a transfer if the shuttle is improperly placed but such mechanisms do not ordinarily operate satisfactorily unless the shuttle is widely misplaced. It is an important object of my present invention to provide means for stopping the loom when a shuttle is improperly placed regardless of whether a transfer has been revoked by wide misplacement of the shuttle or has taken place because of a slight misplacement.

It is a further object of my present invention to provide an electric switch on the shuttle feeler which is normally open and will move into the path of the shuttle when a replenishing operation of the loom is called. If the shuttle is properly placed the switch remains open, but if the shuttle is misplaced beyond the limits of safe transfer the switch will be closed and a solenoid energized to move a stopping dagger on the loom shipping mechanism into the path of a knock-off bunter on the lay. In one application of my invention the switch is closed when the advancing lay is approximately one and one-half inches behind front center. There is adequate time in the remaining forward beat of the lay for energization of the solenoid and movement of the dagger to knock-off position so that a stopping impulse can be given during the last part of the forward stroke of the lay. By having the loom brake set sufficiently close the loom can be stopped just before the lay reaches top center or picking position, and should either of the bobbins involved in the transferring operation be improperly

placed no damage will be done, since picking will have been prevented.

Inasmuch as the electric switch is light in weight and can be operated by a very small force I am enabled to locate the shuttle feeler on which the switch is mounted in a position in front of that heretofore necessary. The practical advantage of so locating the shuttle feeler is that the shuttle has more time in the forward sweep of the lay to reach its shuttle box. In certain former constructions where the shuttle feeler projected rearwardly a considerable distance into the path of the shuttle it was necessary to set the picking at the opposite end of the loom in such a way as to drive the shuttle with an excessive force so that it could pass beyond the shuttle feeler before reaching the latter on its forward motion.

The bobbins of weft replenishing looms ordinarily have three spaced rings which are held by the spring jaws of the shuttle. Although it is desirable to have all three of the springs held by the jaws, a satisfactory transfer can be effected on certain conditions if only two of the rings are held. A shuttle can therefore be misplaced by an amount equal to the distance between adjacent rings and still effect an adequate transfer. It is a further object of my present invention to mount the electric switch on that side of the shuttle feeler opposite the boxed shuttle and make the shuttle feeler of a thickness not substantially greater than the space which separates the rings. In this way provision is made for a slight misplacement of the shuttle within a range of tolerance which will permit adequate transfer.

With these and other objects in view which will appear as the description proceeds, my invention resides in the combination of parts hereinafter described and set forth.

In the accompanying drawings, wherein a convenient embodiment of my invention is set forth,

Fig. 1 is an end view of a loom equipped with my invention, certain parts being in section,

Fig. 2 is an end view of the weft replenishing mechanism as viewed from the center of the loom, the lay being in section,

Fig. 3 is a front elevation looking in the direction of arrow 3, Fig. 2 of the switch resetting mechanism,

Fig. 4 is a front elevation in the direction of arrow 4, Fig. 2 certain parts being in section,

Fig. 5 is a rear elevation taken in the direction of arrow 5, Fig. 1, certain parts being in section,

Fig. 6 is a plan view in the direction of arrow 6, Fig. 1,

Fig. 7 is a diagrammatic view showing the elec-

tric circuit which is controlled by my invention, Fig. 8 is a detailed vertical section on line 8—8, Fig. 1 on an enlarged scale, and

Fig. 9 is a diagrammatic operating view showing parts of the stopping mechanism in the position they assume when the loom is stopped.

Referring to the drawings, I have shown a loom frame 10 having a lay L mounted on lay swords 11, one of which is shown in Fig. 1. The lay moves about the usual rocker shaft 12 at the bottom of the loom and is reciprocated backwardly and forwardly by means of connectors one of which is shown at 13. The lay has a shuttle box B which receives the shuttle S and is provided with a slot 14 for the outgoing bobbin the path of which is directed forwardly by a bobbin chute 15 on the lay. Projecting forwardly from the lay is a transfer bunter 16.

The weft replenishing mechanism comprises a magazine M having in the present instance four guideways 20 for distinctively colored reserve wefts. Forming part of the magazine is a transferrer arm 21 pivoted as at 22 to the magazine and having pivoted thereto a latch holder 23. The latter has secured thereto and projecting rearwardly therefrom a transfer latch 24 which is normally in low position out of the path of the bunter 16. The transferrer arm has a heel 25 which acts to transfer a reserve bobbin designated at R into the shuttle S when the lay approaches front center. The bobbin R may be held in transfer position by supports 26.

The magazine may be of the type shown generally in prior Patent No. 1,030,740 and comprises vertical slides 30, one for each of the reserve stacks of bobbins. When a transfer is called by the weft detecting mechanism not shown the slide corresponding to the indicating shuttle is first raised and then later lowered to release a reserve bobbin from the associated stack so that it can move to the transfer position indicated in Fig. 1.

At the time the magazine is set for transfer the latch 24 is raised from its normally down position into the path of the bunter 16, by means of a rod 32 which extends to the upper part of the magazine and is controlled in a well-known manner. Simultaneously with the lifting of the latch a shuttle feeler 35 pivoted at 36 to the magazine is lowered from its dotted to the full line position shown in Fig. 2, this lowering being accomplished by means of a rod 37 which acts in timed relation with rod 32.

Operation of the loom is controlled by shipper mechanism including a shipper handle 40 fastened to a shipper shaft 41 extending across the loom, and a brake handle 42 which turns freely on shaft 41. The brake handle has a depending arm 43 provided with a stud 44 which enters a slot 45 of a short lever 46 movable about a fixed stud 47 on the loom frame. Pivoted to lever 46 is a link 48 connected to a brake lever 49. When lever 46 is down in the dotted line position of Fig. 1 the brake not shown is on to hold the loom from operating. A spring 50 is connected to link 48 and slot 45 has a notch 51 to receive stud 44. When the brake lever 42 is pulled forwardly or to the left to the full line position of Fig. 1, lever 46 and link 48 move to raise brake lever 49, thereby freeing the loom, and stud 44 enters notch 51 to hold the brake lever yieldingly in running position. Spring 50 is under tension at this time and helps to hold stud 44 yieldingly in the notch.

An upright lever 53 pivoted to the loom frame at 54 has a cam face 55 formed with a notch 56 to receive a stud 57 on the shipper handle 40. A rod 58 pivoted to lever 53 extends rearwardly to control the driving mechanism not shown. A tension spring 59 tends to move the lever 53 rearwardly, or to the right, Fig. 1, to disconnect the driving connections of the loom, and serves also to hold stud 57 in notch 56 during running of the loom. A screw 60 adjustably mounted on the shipper handle is positioned for engagement with a lug 61 on the brake handle to require the shipper handle to move to stopping position, dotted lines Fig. 1, whenever the brake handle moves to apply the brake, also dotted lines, Fig. 1.

In order to start loom operation the levers 40 and 42 will be moved from the dotted to the full line position in Fig. 1, the shipper lever 40 setting the clutch not shown in driving position and the brake handle 42 releasing the brake not shown. Under these conditions the lay will be reciprocated back and forth and other mechanisms of the loom not shown will perform their normal functions. It is thought sufficient for purposes of the present invention to state that when the handles 40 and 42 are in the full line position shown in Fig. 1 the loom is in operation, but when the handles are moved to the dotted position of that figure the loom will be stopped.

During normal operation the shuttle will eventually become depleted and the magazine will be set for a transferring operation by lifting of the latch 24 into the path of the bunter 16 while the lay is in a rearward position and by depression of the shuttle feeler 35 from the dotted line to the full line position in Fig. 2. The shuttle enters the shuttle box as the lay is advancing and should be properly positioned to receive the incoming bobbin, but it is not always completely boxed. If the shuttle is in the position in dotted lines in Fig. 4 it is too widely misplaced for transfer and as the lay moves forwardly the shuttle will engage the rear curved surface 63 of the shuttle feeler to raise the latter, thereby elevating rod 37 which through well-known mechanism will depress rod 32 and allow the latch 24 to fall out of the path of the bunter 16 to prevent transfer. If, on the other hand, the shuttle should be properly positioned as indicated in full lines in Fig. 4 the shuttle feeler will remain down long enough to permit engagement of the bunter 16 with the latch 24 to effect transfer of the reserve bobbin into the shuttle. Continued forward motion of the lay, however, will cause engagement between the box back 64 and the shuttle feeler to raise the latter for the purpose of resetting the magazine. For further reference to the structure and operation of the parts of the mechanism thus far described reference may be had to the following patents: Nos. 1,030,748 and 2,055,229.

As heretofore constructed the connections between the shuttle feeler and the latch 24 have been insufficient to prevent a transfer if the shuttle is only slightly misplaced, and in an attempt to correct this condition the shuttle feeler is set rearwardly with respect to the front position of the lay a sufficient distance to require a strong pick of the shuttle toward the magazine which not only subjects the picking mechanism to unnecessary wear but also is likely to cause sufficient rebounding of the shuttle to leave the latter in wrong position for transfer. It is the general purpose of my pres-

ent invention to provide for stopping the loom should the shuttle be misplaced a slight amount sufficient to interfere with proper transfer but insufficient to revoke transfer through the shuttle feeler when the picking mechanism at the opposite end of the loom is set for proper picking operation.

In carrying my invention into effect I provide means preferably carried by the shuttle feeler to be operated by a slightly misplaced shuttle to effect loom stoppage for the purpose of preventing picking immediately after the normal time of transfer should the mechanical shuttle feeler fail to revoke the replenishing operation. Under these conditions transfer will occur but subsequent picking will be prevented. An electric switch 70 is pivoted as at 71 to the shuttle feeler 35 and is restrained as to its angular motion with respect to the shuttle feeler by a pin 72 on the shuttle feeler projecting through an opening 73 in the switch. The lower end of the switch is provided with a curved surface 74 which conforms more or less in outline to the shape of the adjacent part of the surface 63. The shuttle feeler is provided with a block of insulating material 75 on which is mounted a switch prong 76 having the forward end thereof positioned in the path of the rear arm 77 of the switch.

A resetting rod 80 is secured as at 81 to the magazine frame projects downwardly and is offset as at 82 to overhang a part of the switch, as suggested in Fig. 3. When the shuttle feeler is in its normal raised position indicated in dotted lines in Fig. 2 the rod 80 presses downwardly on the forward end of the switch to move the arm 77 away from the prong 76. Under normal conditions, therefore, there is no contact between the switch and the prong. A small spring 78 serves as a friction device to hold the switch in any position to which it may be moved with respect to the shuttle feeler 35. When the shuttle feeler starts down from the dotted line position shown in Fig. 2, the switch will be open and will remain open with the lower end thereof projecting below and behind the surface 63 on the shuttle feeler. As indicated in Fig. 3 the switch is preferably on that side of the shuttle feeler 35 opposite the magazine and boxed shuttle.

The arm 43 of the brake handle 40 is provided with a knock-off dagger 85 having a rearwardly facing notch 86. The dagger is mounted for pivotal motion around the stud 44 and is normally held in raised position by a tension spring 87 the upper end of which is fixed with respect to the loom as at 88, while the lower end thereof is attached to the latch. A bunter 90 is secured as at 91 to the bobbin chute and swings backwardly and forwardly with the lay. The latch 85 is normally held by the spring 87 in a position above the path of the bunter 90.

Connected to the bunter 90 is a rod 92 which extends downwardly to have contact with the core 93 of a solenoid 94 fixed to the frame as by a stand 95. The latter is capable of limited vertical motion by means of the bolts 96 and slot 97, and a stop 98 formed as part of the stand 95 limits upward motion of the core 93, as by engagement with the pivot pin 99, see Fig. 5, by which the rod is connected to the core 93.

The electrical connections between the switch and the solenoid are set forth in Fig. 7, where it will be seen that the switch 70 is connected

by means of wire 100 to one side of the solenoid 94, while the other side of the solenoid is connected by wire 101 to a low voltage transformer 102. A third wire 103 connects the other side of the transformer to the prong 76.

In operation, the switch 70 is normally kept in open position and the shuttle feeler 35 is raised, hence spring 87 can lift the latch 85 out of the path of the bunter 90. Under these conditions 10 the latch 85 is in its rear position due to the fact that the shipper handle has been pulled forwardly to cause loom operation. When a transfer is called the shuttle feeler will be lowered and when it assumes the down position 15 shown in Fig. 1 the surface 74 of the switch 70 will extend beyond the outline of the surface 63 and into a position where it can be engaged by a misplaced shuttle. Should the shuttle be properly boxed it will move forwardly along a path at one side of the switch 70 and the latter will 20 therefore remain open and a transfer will take place in the usual manner. Continued forward motion of the lay will cause the box back 64 to raise the shuttle feeler as already described without contacting the switch 70.

The shuttle may not be placed properly for transfer, in which case it may be either slightly misplaced and unable to raise the shuttle feeler to prevent transfer, or it may be misplaced 25 widely enough to raise the shuttle feeler and prevent transfer. If the shuttle be only slightly misplaced, it will engage the switch 70 as the lay advances and move the switch to the position shown in Fig. 2, thereby establishing contact between the prong 76 and the switch arm 77. Current will thereupon flow through the circuit shown in Fig. 7 to energize the solenoid 94 the effect of which is to draw the core 93 downwardly against the action of spring 87 and lower the latch 85 into the path of the bunter 90. As the lay continues to move engagement 30 of the latch 85 with the bunter 90 will rock the brake handle from the full to the dotted line position in Fig. 1, thereby rocking the shipper handle to stopping position due to screw 60 and lug 61, thus disconnecting the loom from its driving motor and at the same time applying the brake. This last operation occurs during advance of the lay, and if the shuttle has not been 35 able to raise the shuttle feeler because of its slight misplacement, transfer will occur before the loom stops. The brake will ordinarily be set to stop the loom before the lay reaches top center or picking position in its ensuing backward motion.

It will therefore be seen that a very small displacement of the shuttle will operate to stop the loom, and even though the shuttle feeler is not able to prevent an improper transfer there will be no danger of picking a shuttle with an 40 improperly located reserve bobbin therein.

When the shuttle is widely misplaced it will 45 first close the switch to initiate loom stoppage as already described, and then raise the shuttle feeler to prevent transfer. The rod 80 will act to open the switch when the shuttle feeler is restored to its normal position by the misplaced shuttle. The interval between closing of the switch by the misplaced shuttle and its opening by the rod 80 is long enough, however, to 50 permit sufficient energization of the solenoid to draw the latch 85 down into the path of the bunter 90.

The front wall of the shuttle will ordinarily 55 be lower than the top part of the box back 64

and will therefore act on the switch 70 even though the latter is not effected by the box back due to the fact that the latter engages the shuttle feeler surface 63 at a point higher than the shuttle wall. Regardless of the condition of transfer, the lay will always move to front center position and will therefore raise the shuttle feeler and cause the rod 80 to break the contact between the prong 76 and the switch arm 17, hence there is no danger that the solenoid will remain energized after the loom has been stopped. As the circuit is broken the spring 87 is free to raise the latch 85. It is a characteristic of loom shedding mechanism, particularly the type shown in Fig. 1, that as soon as stud 44 is unseated from the notch 51, the shipper handle will move to stopping position. When the loom is fully stopped, therefore, the latch 85 will be in a position forward of the bunter 90 even when the lay is on front center position, and under these conditions the latch 85 is held above the bunter so that the shipper handle can be pulled on without engagement of the latch 85 with the bunter 90.

When the brake handle arm 43 moves to the position shown in dotted lines in Fig. 1, the pivot of latch 85 will move downwardly while the spring 87 holds the latch 85 up, therefore the rear end of the latch will be inclined upwardly as indicated in Fig. 9 and this is an additional reason why the shipper handle may be moved to running position after the loom has stopped without causing objectionable engagement between the latch 85 and the bunter 90.

As shown particularly in Figs. 3 and 4 the electric switch is located on that side of the shuttle feeler opposite the boxed shuttle, the reason for this location being to permit a small amount of misplacement of the shuttle without necessarily stopping the loom. The shuttle 8 to be replenished will ordinarily have bobbin holding spring clips 110 which engage the rings 111 on the head 112 of the bobbin 113. It is desirable that all three of the rings on the bobbin be held by the shuttle jaws, but it is possible to effect a satisfactory transfer if only two of the rings are held, and this condition will exist if the shuttle is not misplaced by a distance greater than the distance between adjacent bobbin rings. It is customary to set the shuttle feeler so that its right hand surface 115, see Fig. 4, which faces the shuttle will be close to the shuttle tip when the shuttle is properly boxed. By placing the switch on the opposite side of the shuttle feeler and making the latter of a thickness not exceeding the distance between two adjacent rings on the bobbin head the shuttle can assume a position slightly to the right of that shown in full lines in Fig. 4 without closing the switch. Under these conditions a transfer will occur, since the mechanically operating shuttle feeler will be too slow to revoke the replenishing operation, but the incoming bobbin will be adequately supported by the shuttle clips and there is no necessity for stopping the loom. By locating the switch as described the shuttle can be replenished and loom operation continued if the misplacement of the shuttle is within a narrow range of tolerance the extent of which is determined by the distance between adjacent rings on the bobbin head. If the shuttle is misplaced by an amount exceeding this range the shuttle tip will be able to strike the switch and the loom will be stopped. With this somewhat greater displacement only one ring of the bobbin head would

be held by the shuttle jaws, a condition which is not considered satisfactory for proper weaving. While the relationship described is a feature of the construction as shown in Figs. 4 and 5, I do not wish necessarily to be limited to such a location of the switch relatively to the shuttle feeler and shuttle.

From the foregoing it will be seen that I have provided simple means for stopping the loom should the shuttle be improperly placed for a correct transfer. It will also be seen that normal raising of the shuttle feeler due to forward motion of the lay results in opening the switch so that the solenoid is not subjected to continued energization during the period that the loom is stopped. Also, even though the shuttle feeler will not act in response to a slightly misplaced shuttle to revoke a transfer, the loom will nevertheless be stopped to avoid the risk of picking a shuttle containing an improperly transferred bobbin. Again, the switch will remain closed during practically all of the upward motion of the shuttle feeler induced by the box back, therefore providing sufficient time for the solenoid to effect loom stoppage even though transfer is mechanically revoked by the shuttle feeler. An advantage growing out of this relationship is the fact that the weaver's attention is called to the improper picking from the opposite side of the loom which results in the faulty location of the shuttle. As a further feature, the movement of the shipper handle and the relation of the rod 92 to the latch 85 and the connections of the latter are such that the shipper handle may be pulled on after the loom has been stopped without danger of forcing the latch against the bunter. It will further be seen that the switch is on that side of the shuttle feeler opposite the boxed shuttle, thereby making provision for a slight misplacement of the shuttle throughout a rather narrow range within which adequate transfer can occur.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom operating with a lay having a shuttle box containing a shuttle to receive a reserve bobbin in a weft replenishing operation of the loom during a forward motion of the lay, a carrier normally in non-operative position and movable into operative position preparatory to a weft replenishing operation of the loom while the lay is moving forwardly, a normally open electric switch on the carrier and having a portion projecting from said carrier toward the path of the shuttle when said carrier is in operative position, said switch located to be out of engaging position with the shuttle during forward motion of the lay when the shuttle is properly boxed for a weft replenishing operation and located for engagement with the shuttle when the latter is improperly boxed for a proper weft replenishing operation, and electromagnetically controlled means to stop the loom when a shuttle projects far enough from the shuttle box to engage and close the switch.

2. In a weft replenishing loom operating with a lay having a shuttle box containing a shuttle to be replenished from a reserve bobbin magazine during a forward motion of the lay, the loom having a shuttle position detecting

feeler movable from normal position out of the path of the shuttle to detecting position into the path of the shuttle preparatory to a weft replenishing operation of the loom, and a weft replenishing operation of the loom being prevented if the shuttle is widely misplaced and moves the shuttle feeler toward normal position, an electric switch normally open and mounted on said shuttle feeler and having a portion projecting beyond the shuttle feeler toward the path of the shuttle when said feeler is in detecting position, said switch located to be out of engaging position with the shuttle during forward motion of the lay when the shuttle is properly boxed for a weft replenishing operation and located for engagement with the shuttle to be closed thereby when the shuttle is improperly boxed for a proper weft replenishing operation, and electromagnetically controlled means to stop the loom when said switch is closed, a shuttle protruding from the shuttle box too far for a proper weft replenishing operation preventing a replenishing operation by movement of the shuttle feeler and closing said switch to effect loom stoppage.

3. In a weft replenishing loom operating with a lay having a shuttle box containing a shuttle to be replenished from a reserve bobbin magazine during a forward motion of the lay, the loom having a shuttle position detecting feeler movable from normal position out of the path of the shuttle to detecting position into the path of the shuttle preparatory to a weft replenishing operation of the loom, and a weft replenishing operation of the loom being prevented if the shuttle is widely misplaced and moves the shuttle feeler toward normal position, stopping mechanism for the loom, an electromagnetically actuated controller for the stopping mechanism, an electric switch normally open and mounted on the shuttle feeler and movable with the latter toward the path of the shuttle, a misplaced shuttle protruding too far from the shuttle box for proper transfer engaging and closing the switch during forward motion of the lay, and electrical means controlled by the switch to actuate the electromagnetic control to stop the loom, whereby a misplaced shuttle prevents a replenishing operation by movement of the shuttle feeler and also stops the loom.

4. In a weft replenishing loom operating with a lay having a shuttle box containing a shuttle to be replenished from a reserve bobbin magazine during forward motion of the lay, a shuttle position detecting feeler movable from normal position to detecting position preparatory to a weft replenishing operation of the loom, a normally open electric switch mounted on the shuttle feeler and movable with the latter to detecting position, a loom controlling handle normally in running position and movable to stopping position to stop the loom, means moving with the loom controlling handle normally in non-stopping position, a lay carried bunter normally clearing said means during forward motion of the lay, an electromagnetic controller for said means, and electric connections between the switch and the electromagnetic controller to energize the electro-magnetic controller when the switch is closed, a shuttle which protrudes too far from the shuttle box for a proper replenishing operation closing the switch during forward motion of the lay to cause energization of the electromagnetic con-

troller and the latter moving said means into the path of the bunter carried by the lay to effect movement of the loom controlling handle toward stopping position during forward motion of the lay.

5. In a weft replenishing loom operating with a lay having a shuttle box containing a shuttle to be replenished from a reserve bobbin magazine during forward motion of the lay, a shuttle position detecting feeler movable from normal position to detecting position preparatory to a weft replenishing operation of the loom, an electric switch on the shuttle feeler normally open and having a portion thereof projecting beyond the shuttle feeler toward the path of the shuttle when said shuttle feeler is in detecting position, loom stopping mechanism, an electromagnetic controller for said mechanism, and electric connections including the switch and the electromagnetic controller to energize the latter when the switch is closed, a shuttle protruding too far from the shuttle box for a proper replenishing operation engaging and closing the switch and the electromagnetic controller thereupon causing the loom stopping mechanism to stop the loom.
6. In a weft replenishing loom operating with a lay having a shuttle box containing a shuttle to be replenished from a reserve bobbin magazine during forward motion of the lay, a shuttle position detecting feeler movable from normal position to detecting position preparatory to a weft replenishing operation of the loom, a loom controlling handle normally in running position and movable to stopping position to stop the loom, a dagger pivoted to the loom controlling handle, a bunter on the lay for engagement with the dagger, means to hold said dagger normally out of the path of the bunter as the layer moves forwardly, an electric switch on the shuttle feeler normally open and having a portion thereof projecting beyond a shuttle feeler and toward the path of the shuttle when the shuttle feeler is in detecting position, an electromagnetic means electrically connected to the switch for energization when said switch is closed, and mechanism operated by the electromagnetic means and connected to said dagger to move the latter into the path of the bunter when the electromagnetic means is energized, a shuttle protruding too far from the shuttle box for proper weft replenishing operation closing the switch during forward motion of the lay to energize the electromagnetic means and the latter upon being energized moving the dagger into the path of the bunter, whereupon the latter acts during forward motion of the lay to move said dagger and cause movement of the loom controlling handle to stopping position.
7. In a weft replenishing loom operating with a lay having a shuttle box containing a shuttle to be replenished from a reserve bobbin magazine during forward motion of the lay, a shuttle position detecting feeler movable from normal position to detecting position preparatory to a weft replenishing operation of the loom, a normally open electric switch mounted on the shuttle feeler and having a portion projecting from the feeler toward the path of the shuttle when said shuttle feeler is in detecting position, an electric solenoid, a core for said solenoid, a loom controlling handle normally in running position and movable from running to stopping position to stop the loom, a dagger movably mounted

on said handle and normally in running position, connections between the core and the dagger to move the latter to stopping position when the solenoid is energized, a bunter mounted on and moving forwardly with the lay, means normally to hold the dagger yieldingly out of the path of the bunter, and means to energize the solenoid when the switch is closed, a shuttle protruding from the box too far for proper weft replenishing operation engaging and closing the switch to energize the solenoid and the latter thereupon moving the core to effect movement of the dagger into the path of the bunter during forward motion of the lay, said bunter and latch cooperating to move the handle to stopping position.

8. In a weft replenishing loom operating with a lay having a shuttle box containing a shuttle provided with a bobbin having spaced rings which are held by the shuttle, adjacent rings being separated by a given distance, a shuttle position detecting feeler normally out of the path of the shuttle and movable into the path of the shuttle preparatory to a weft replenishing operation to a position closely adjacent to the inner end of the shuttle when the latter is properly boxed, a normally open switch on the shuttle position feeler on the side thereof opposite the shuttle box and having a portion protruding into the path of the shuttle when the shuttle positioned feeler is in detecting position, and electromagnetically controlled means to effect loom stoppage when said switch is closed, said switch being spaced from the adjacent end of the shuttle when the latter is properly boxed by a distance not substantially greater than said given distance between adjacent rings, a shuttle being misplaced from normal position by a distance greater than said given distance closing the switch to effect loom stoppage.

9. In a weft replenishing loom operating with a lay having a shuttle box containing a shuttle provided with a bobbin having spaced rings which are held by the shuttle, adjacent rings being separated by a given distance, a shuttle position detecting feeler normally out of the path of the shuttle and movable into the path of the shuttle preparatory to a weft replenishing operation to a position closely adjacent to the inner end of the shuttle when the latter is properly boxed, said shuttle positioned feeler having a thickness measured in the direction of the length of the lay not substantially in excess of said given distance, a normally open switch on the feeler on the side thereof opposite the shuttle box, and electromagnetically controlled means to stop the loom when the switch is closed, a shuttle protruding from the shuttle box by a distance in excess of said given distance closing the switch to effect loom stoppage.

10. In a weft replenishing loom operating with a lay having a shuttle box containing a shuttle provided with a bobbin having spaced rings which are held by the shuttle, adjacent rings being separated by a given distance, a shuttle position detecting feeler normally out of the path of the shuttle and movable into the path of the shuttle preparatory to a weft replenishing operation to a position closely adjacent to the inner end of the shuttle when the latter is properly boxed, a normally open electric switch on the shuttle feeler having a part to project beyond the shuttle feeler into the path of the shuttle at a point not substantially farther from the inner end of the shuttle when the latter is prop-

erly boxed than said given distance when the shuttle feeler is in detecting position, and electromagnetically controlled means to stop the loom when said switch is closed, a shuttle protruding from the shuttle box by a distance in excess of said given distance closing the switch to stop the loom.

11. In a weft replenishing loom operating with a reciprocating lay having a shuttle box containing a shuttle to receive a reserve bobbin during a weft replenishing operation of the loom, a shuttle position detecting feeler movable from normal position out of the path of the shuttle to a detecting position into the path of the shuttle preparatory to a weft replenishing operation of the loom and subsequently movable back to normal position by the lay after the weft replenishing operation, an electric switch mounted on the shuttle position feeler, means to cause the switch to be open when the shuttle feeler is in normal position, switch controlling means to maintain the switch open when the shuttle feeler moves to detecting position, said switch having a part projecting beyond the feeler into the path of the shuttle when the shuttle feeler is in detecting position, and electromagnetically controlled means to stop the loom when the switch is closed, a shuttle protruding from the shuttle box too far for a proper weft replenishing operation closing the switch to effect loom stoppage during the latter part of the forward motion of the lay, and said switch controlling means operating to open the switch when the shuttle feeler returns to normal position.

12. In a weft replenishing loom operating with a lay having a shuttle box containing a shuttle to be replenished from a reserve bobbin magazine, a shuttle position detecting feeler normally out of the path of the shuttle and movable into the path of the shuttle preparatory to a weft replenishing operation, the shuttle feeler returning from detecting to normal position when the lay reaches its front position on a weft replenishing beat of the loom and a weft replenishing operation being prevented when said shuttle positioned feeler is returned to normal position by a widely misplaced shuttle before the lay reaches front position, a normally open electric switch on the shuttle feeler having a portion projecting from said feeler into the path of the shuttle when the shuttle feeler is in detecting position, and electromagnetically controlled loom stopping mechanism to effect loom stoppage when the switch is closed, a widely misplaced shuttle protruding too far from the shuttle box on a weft replenishing beat of the loom for proper transfer closing the electric switch and moving the shuttle feeler to normal position to prevent a weft replenishing operation, and said switch to be closed by a slightly misplaced shuttle to initiate loom stoppage on the beat of the loom on which weft replenishment is effected.

13. A shuttle position detecting feeler having a shuttle engaging surface of given contour, an electric switch movably mounted on and supported by the shuttle feeler, said electric switch capable of assuming two positions with respect to the feeler in one of which the switch is open and in the other of which the switch is closed, said switch when open having a shuttle engaging surface thereof projecting outwardly from said contour of the feeler, and said electric switch when in closed position having the shuttle engaging surface thereof in substantial alignment with said given contour of the feeler.

14. A shuttle position detecting feeler for a weft replenishing loom, said feeler having a shuttle engaging surface of given contour, an electric switch pivoted to the feeler, an electric contact carried by the feeler in position for engagement with the switch, said electric switch having a portion thereof which projects beyond said given

5 contour when the switch is spaced from said contact, and said switch movable pivotally into engagement with said contact when the shuttle engaging surface thereof is moved in substantial alignment with said given contour.

CLIFFORD DARWIN.
